E. G. DE BARY

GAME INSTRUMENT FOR POKER AND SIMILAR CARD GAMES

Original Filed April 30, 1921

Patented Oct. 30, 1928.

UNITED STATES PATENT OFFICE.

ERVIN GUSTAVE DE BARY, OF AMSTERDAM AND KOTTACH-TEGERNSEE, GERMANY.

GAME INSTRUMENT FOR POKER AND SIMILAR CARD GAMES.

Application filed April 30, 1921, Serial No. 465,866, and in Germany May 12, 1920. Renewed August 18, 1927.

My invention relates to a game-instrument intended primarily for card games where the cards remain in the hands of the player and by which poker and other card games may be played without playing cards and under conditions where a table might not be available, as in traveling. And my purpose is to obtain by mechanism—instead of by shuffling and dealing or other manual methods—a free and chance distribution or assemblage of the game symbols—card symbols in the preferred arrangement—into a group or hand of the proper number of constituent units, and to do this by a very compact and effective arrangement and structure. The preferred embodiment of the invention includes means for assembling the symbols used in playing the game into two groups, one corresponding with the deal or hand proper, and the other with the draw.

To this end I provide a series and preferably two series of disks, each bearing a set of symbols—as playing card symbols—and mounted for free rotation in a casing having, opposite the symbol-carrying face of each disk, an aperture of a size to disclose at any given time one only of said symbols, the rest being screened from view by the casing. And I employ manually operable, or controllable, means for simultaneously rotating the disks of one or both series, and then automatically and simultaneously freeing them for individual rotation. It is most convenient to arrest the individual disks simultaneously, and means for so arresting them may and ordinarily would be added.

The employment of two series of disks is novel and advantageous, particularly in playing a draw game such as poker, and the compact arrangement and the operating mechanism has more than a merely specific novelty and advantage.

Further features of my invention will appear in the detailed description here following, and will be pointed out in the claims.

Referring to the drawings:

Figure 1 is a top view of the front or obverse of my new game instrument;

Fig. 2 is a horizontal section through the same, showing the internal construction;

Fig. 3 is a vertical section on the line A—B of Fig. 2;

Figs. 4, 5, 6 and 7 are detail views on a larger scale, Figs. 4, 6 and 7 being sections

taken respectively on lines C—D, E—F, and G—H.

The new device has preferably the shape and appearance of a watch and, in its preferred form, comprises two concentric series of five or any number (according to the game to be played) of disks, upon which are placed sets of symbols used in the game, e. g., the cards belonging to a pack. These disks of each series, or of both series, may be simultaneously set to rotating, or respectively arrested in positions in which one card only on each disk is visible. Of the two sets of symbols visible, one serves to apportion the cards which in dealing would come to each player, while the other is intended for the apportionment of those cards which each player would receive in the course of the game. Both series may be located within a common casing and so arranged, for instance, that one series of five disks rotates beneath the face or obverse side of the case and the other beneath the reverse.

The simultaneous rotation of the disks of each series may be effected by winding up a spiral or watch-spring, and by means of a spring-actuated and inward moving push.

If one series of disks is superimposed upon the other in a common case the starting spring or push may be common to both, as may also the arrester. The latter may comprise another push to effect a return movement of the central wheel or wheels herein-after referred to, when placed in connecting position with the said rotatory disks, and a stoppage of the central wheels.

The drawing shows a watch-case *a* in which the disks are disposed in circular series concentric with each other and with the case, being conveniently located respectively as illustrated on opposite sides of a transverse partition *b* parallel to the long axis of the case, the disks *c* and *d* being preferably mounted loose on the common shafts *i*, *k*, each disk *c* being connected with a gear wheel *g* and each disk *d* with a gear wheel *h*. The gear wheels *g* are in mesh with a centrally located gear *e* fast to the shaft *l* on which also is fast the gear *f* which meshes with the gears *h*. On the shaft *l* is also mounted the common starting gear wheel *m* by which the shaft is driven. The toothed wheel *m* receives its rotation from a spring-actuated pin or push *n* provided with a rack *o* whenever the said

push n is moved inward in opposition to the action of the spring p . The shaft l is supported in a vertically movable frame q (see Figs. 3 and 4). This frame is under the 5 action of a releasing lever r and a returning spring or weight. Movement of the lever r transversely of the shaft l may be readily provided for as by the slot r^1 . The lever r may be immediately actuated by a slide t mounted 10 on the partition b and being, respectively, subject to the action of the starting push n and to that of another push u serving to stop the rotation of the respective card disks. The starting push n hits the slide t and pushes it 15 beyond the lever-end v . This occurs as soon as the rack-portion o of the push has passed over, or approximately over, the toothed starting wheel m . In this way pressing in the push n rotates the disks, whereupon the 20 lever r is actuated and lifts the frame q with the starting wheel m and the two central wheels e, f , the starting-wheel m getting out of the path of the rack-portion o , while the central wheels e and f become disengaged 25 from the wheels g, h and thus get out of connection with the card disks c, d , the latter continuing their rotations freely. Unless it is preferred that they run out until exhausted, the rotation may be stopped by an inward 30 movement of the arresting-pin u at any desired moment. For this purpose the said arresting-push u is provided with a detent w engaging the starting wheel m and with a tooth x , acting to return the slide t . By the 35 return movement of the said slide t the lever r is released, permitting the frame q to go down again. In this way the starting-wheel m gets again within the path of the rack-portion o of the starting push n which has in 40 the meantime returned, and the central gears e and f resume connection with the wheels g and h . Preferably the push u may be provided with a detent permitting its retention in arresting position until the disks c, d are 45 again rotated. After the disengagement of this detent the return of the push u may be automatically accomplished by a rearward acting spring y .

The card-disks c, d may, for instance, be 50 divided in six and, respectively, seven compartments each of which is to receive one of the pictures of a pack of cards, the compartments of the set c together with those of the set d showing up in this way all of the several cards belonging to a pack.

Above these card-disks c, d there is over each a transparent opening z of the size of a compartment, so that when the disks c and d have after rotation come to a stop, one compartment, that is, one card picture will be 60 exhibited. The card pictures thus shown on the obverse face of the instrument represent the cards which the player receives and those exhibited on the reverse denote those cards 65 which the player is in accordance with the

rules of the game entitled to exchange for those on the front face. To permit such an exchange the opening z on the obverse and reverse faces may be provided with symbols or characters, as for instance, numerals appearing in equal pairs. Suppose, for instance, a player says, he wishes to exchange the cards exhibited by equal openings 3 and 5, the instrument is turned upside down and the cards exhibited by the corresponding 70 openings on the reverse face are those which the player has received in the exchange. If the reverse set of disks has a separate starting and arresting device, the cards which the player is to receive in exchange can be determined only after calling the openings and subsequently reversing the instrument. In the other case the openings z of the reverse face may ordinarily be covered by a lid or the like until the player has called out the 85 cards he wants to exchange.

I would mention that the detent or stopping-mechanism or device for the card disks may be so shaped that the disks are retained in a position in which one of its compartments 90 coincides continually with the opening next above.

I claim:—

1. The herein described game-instrument for poker and similar games of cards comprising simultaneously rotatable, and arrestable disks bearing card pictures belonging to a pack and movable each behind an opening through which one card is exhibited by the rotating disk when arrested, and in combination therewith another series of similar disks bearing other card pictures belonging to the same pack exhibited on the reverse side of the instrument.

2. In the herein described game-instrument for poker and similar games of cards comprising series of simultaneously rotatable, and simultaneously arrestable disks bearing pictures of the cards belonging to a pack, as set forth in claim 1, the combination of a simultaneously acting mechanism adapted to set the said series of disks in rotation, and a simultaneously acting mechanism adapted to stop said rotation.

3. A game device comprising a casing of the watch-case type, two series of disks rotatably mounted therein, each bearing game symbols, one series representing the deal and the other the draw, means for freely spinning each of said disks, and means for stopping each of said disks.

4. In the herein described game-instrument for poker and other games comprising circular series each of commonly rotatable and commonly arrestable disks bearing symbols used in playing the game, the said instrument comprising the combination with mechanisms adapted to set the disks of a series in rotation at the same time, and to stop said rotation, axially movable gears concentric with the re- 120

spective series of disks and operatively connected thereto, and a spring-actuated inwardly movable push acting to shift said gears axially to release them from operative connection with said disks.

5. In a game-instrument for poker and similar games comprising sets of commonly rotatable and commonly arrestable disks bearing symbols used in playing the game, as 10 set forth in claim 4, and a second inward movable push adapted to be disconnected from or to be operatively connected with the concentric gears and thereby with the said rotatable disks to cause rotation of the same to be arrested.

6. In a game-instrument for poker and other games comprising two series each of commonly rotatable and arrestable disks bearing symbols used in playing the game, 20 and screened from view save for one symbol on each disk, one of said series of disks representing the deal and the other the draw, and means for actuating and controlling said disks comprising central gears adapted to mesh with and to release smaller pinions operatively connected to respective disks, and means for actuating said central gears.

7. A game-instrument for poker and similar games of cards comprising series each of 30 commonly rotatable and commonly arrestable disks bearing the pictures of cards belonging to a pack, large to small drive gears arranged for operative connection with said disks and for disconnection therefrom, and actuating 35 and controlling means for said disks comprising a bodily shiftable gear for driving and arresting said gearing, and means to operate and to arrest said shiftable gear.

8. In a game-instrument for poker and other games comprising an apertured casing 40 having therein, and partially visible therethrough, series each of commonly rotatable and arrestable disks bearing respectively sets of symbols used in the game, and means for actuating and controlling said disks comprising a central gear around the axis of which said disks are arranged, a series of gears each operatively connected to one of said disks and normally in mesh with said central gear, and 50 an inward push capable of operative engagement with and disengagement from the central gear hereinabove mentioned, to cause the same to operate and then free said disks.

9. A game device comprising a casing, two 55 series of disks rotatably mounted therein, each disk bearing game symbols one series representing the deal and the other the draw, means for rotating each of said disks including gearing to each of said disks, and means 60 for interrupting the gearing to each of said disks.

10. A game device comprising a casing of 65 watch-case type having both sides apertured, two series of disks located adjacent opposite sides of the casing, the disks each facing the

adjacent apertured side and being mounted in the casing for free rotation, the disks of both series having their axes disposed in a circle whose center is the short axis of the casing, each disk bearing a set of symbols used in 70 playing the game and of which only one symbol of each set is visible at any one time through the corresponding aperture, and means mounted in the casing concentrically with the said circle of disk axes and operatively connected to the disks of both series 75 for actuating said disks and for giving those of one set simultaneous rapid rotation and then freeing them for independent individual rotation.

11. A game device comprising an apertured casing of watch-case type, a series of disks mounted therein for free rotation and having their axes disposed in a circle whose center is the short axis of the casing, each disk bearing a set of symbols used in playing the game and of which only one symbol of each set is visible at any one time through the corresponding aperture, means mounted in the casing concentrically with the said circle of disk axes and operatively connected to said disks for simultaneously giving them rapid rotation and then freeing them for independent individual continued rotation, and means for 90 axially shifting said means for giving the 95 disks simultaneous rotation.

12. A device for playing poker or other games comprising an apertured casing, two series of disks rotatably mounted therein, each disk of each series carrying playing-card 100 symbols, one series serving to indicate the deal, and the other the draw, only one card symbol on a given disk being visible at any one time through an adjacent aperture in the casing the rest being covered, and means for 105 setting the disks of both series in rapid rotation and thereafter freeing them for independent individual rotation.

13. A device for playing poker or other games comprising an apertured casing, two 110 series of disks rotatably mounted therein, each disk of each series carrying playing-card symbols, one series serving to indicate the deal, and the other the draw, only one card symbol on a given disk being visible at any one time through an adjacent aperture in the casing the rest being covered, means for setting the disks of both series in rapid rotation and 115 thereafter freeing them for independent individual rotation, and means for arresting the 120 disks.

14. The herein described game-instrument for poker and similar games of cards, comprising a casing, simultaneously rotatable and arrestable disks in said casing facing one side 125 thereof, bearing card pictures belonging to a pack and movable each behind an opening through which one card is exhibited by the rotating disk when arrested, another series of disks in the casing facing the opposite side 130

thereof, each disk bearing other card pictures and movable behind an opening through which one card is exhibited by the rotating disk when arrested, and means for rotating and arresting the several disks.

15. A game device comprising a casing of watch-case type, two concentric series of disks rotatably mounted therein, the disks of one series facing one side of the casing and those of the other facing the opposite side of the casing, sets of game symbols arranged on said disks, and actuating means for said disks located in the space between the planes of the disks of the respective series.

16. A game device comprising a casing of watch-case type, two concentric series of disks rotatably mounted therein, the disks of one series facing one side of the casing and those of the other facing the opposite side of the casing, sets of game symbols arranged on said disks and screened from view except for an opening for each set of a size to display one of the symbols of that set, the openings on each

side of the casing being correspondingly numbered, and means for putting the several 25 disks into rapid rotation, one series of disks serving as the hand and the other as the draw.

17. A game device comprising a casing of the watch-case type, a series of disks rotatably mounted therein and having their axes 30 arranged in a circle, gearing operatively connected to each disk and including a drive gear concentric with said circle and gears connected to individual disks, means for rotating said drive gear, and means for interrupting 35 the gearing connection between said drive gear and individual gears of the disks.

18. A game device comprising a casing, two series of disks rotatably mounted therein, each bearing game symbols, one series representing the deal and the other the draw, means for freely spinning each of the deal disks and means for freely spinning each of the draw disks.

In testimony whereof I affix my signature.
ERVIN GUSTAVE DE BARY.
